UNITED STATES PATENT OFFICE.

RUFUS A. RUSSELL, JR., OF MIAMI BEACH, FLORIDA.

AUTOMOBILE HEADLIGHT.

Application filed July 8, 1925. Serial No. 42,243.

My said invention relates to automobile headlights and it is an object of the invention to provide a headlight which will not only clearly illuminate the roadway immediately adjacent to and at a distance from the front of the vehicle upon which the same is mounted but which will also cast its light upon the edges of the roadway and at a distance to the side of the vehicle upon the adjoining area thus affording a safety of operation not present in the conventional forms of headlights now in use.

A further object of the invention is to provide a device of this character which will not blind a person looking directly into the same but instead will cast a soft mellow sheet of light.

Referring to the accompanying drawings which are made a part hereof and on which similar reference characters indicate similar parts,

Figure 1 is a front elevation of the invention with part of the lens and frame broken away,

Figure 2, a section on line 2—2 of Figure 1, and

Figure 3, a perspective of the reflector.

In carrying out the foregoing objects I provide one elongated reflector which is adapted to be mounted by any desired means across the front of the vehicle and at substantially the same height as the two lights ordinarily used.

The device comprises a casing 10 in which is mounted a reflector 11, said casing being open at one side and being provided with a lens 12. The reflector 11 is provided with a plurality of sockets 13 spaced longitudinally along the central portion of the same and adapted to receive lamps 14. Said reflector 11 is preferably formed with a relatively narrow central longitudinally extending concave portion or trough and is convexly curved between said portion and the upper and lower side edges of the reflector. By this construction light from the lamp 14 striking the concave portion will be projected in strong rays directly ahead while the light rays striking the convex portion of the reflector will be broken up or diffused and will not be concentrated. The reflector 11 is provided with end portions 15 formed substantially the same in cross section as the rear portion of the reflector and serving to project the light beyond the opposite ends of the reflector. Also the light from each of the

lamps 14 will strike the reflector at an angle and be projected at substantially the same angle from the longitudinal center of the reflector.

In order to prevent the rays of light striking the concave central portion of the reflector and being projected upwardly a sufficient distance to blind a person looking at the light I provide a lens as shown in Figures 1 and 2 having a substantially flat plain band 16 extending longitudinally and centrally of the same over the series of lamps 14 but having its upper and lower portions formed to break up the rays of light as for example by frosting or providing the same with angular portions as shown.

The casing for the lens may be provided with any desired means for retaining the reflector therein and for holding the lens in position. It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. A headlight comprising an elongated reflector having a relatively narrow longitudinally extending central depression and provided with convexly curved portions at the upper and lower edges thereof, and a plurality of lights mounted in spaced relation in said depression said reflector having end portions provided with reflecting surfaces similar in cross section to the main body of the reflector, substantially as set forth.

2. A reflector comprising a body having a central longitudinally disposed trough with convex side portions extending upwardly and downwardly therefrom and outwardly extending end portions for said body also having a central longitudinally disposed trough with convex portions extending therefrom and forming reflecting surfaces, substantially as set forth.

3. An automobile headlight comprising an elongated casing, an elongated reflector within said casing having a relatively narrow depression extending longitudinally thereof and providing a reflecting surface and having longitudinally arranged convexly curved reflecting surfaces at the sides of

said depression, and a lens for said headlight having a plain band extending longitudinally over the narrow depression said lens having prismatic portions at each side of said narrow band whereby the light will be reflected from the central depression through the narrow band of the lens directly ahead of the light while the light reflected from the convex longitudinally extending surfaces will be projected toward one edge of the headlight, substantially as set forth.

4. In a headlight the combination of an elongated shallow reflector having a rela-

tively narrow depression extending longitudinally thereof providing a reflecting surface with longitudinally arranged convexly curved reflecting surfaces at the sides of said depression, and a source of light positioned ahead of the convexly curved reflecting surfaces, substantially as set forth. 15

In witness whereof, I have hereunto set my hand and seal at Hendersonville, North Carolina this 6th day of July, A. D. nineteen hundred and twenty-five. 20

RUFUS A. RUSSELL, JR. [L.S.]
